RAY W. CONANT, OF LOS ANGELES, CALIFORNIA, ASSIGNOR TO HAROLD D. BROWN,
OF LOS ANGELES, CALIFORNIA

LOOPER

Application filed August 26, 1929. Serial No. 388,412.

This invention relates to a device for temporarily storing or holding for subsequent use a continuous strip of sheet material as such material issues from a machine in which 5 operations thereon have been performed.

In the manufacture of roofing material, to which art the invention is particularly valuable, the roofing paper issues in a continuous manner from a machine in the form of a continuous strip. Where the strip is to be then operated on by a machine, and especially where such second machine is non-continuous in its operation, a temporary storage device, called a looper, is disposed between the first 10 and second machines, this looper having means for supporting the strip of material issuing from the first machine in the form of suspended loops. The feeding of the endless strip of material to the looper or storage 15 device may be continuous, and the withdrawal of the strip of material for subsequent operation may be non-continuous.

My invention relates to a looper or storage device of the above character having a device 20 associated therewith for preventing disalignment of the strip of sheet material and as a result thereof eliminating the breakage of the strip of sheet material due to such disalignment.

A further object of the invention is to 25 provide a simple form of device of the character set forth in the preceding paragraph which will operate in frictional engagement with the end loop of a series of loops of sheet 30 material held in a looper, and by such frictional engagement will prevent such disalignment or twisting in the end loop as ordinarily results in breakage of the strip.

A further object of the invention is to 35 provide in a looper a breakage preventing device which is adapted to automatically assume a yielding position against the final or leaving loop of a strip of sheet material.

A further object of the invention is to 40 provide a device of the above character having means for adjusting the pressure with which a restraining means is held in engagement with the final loop of a strip of sheet material.

50 It is a further object of the invention to

provide a restraining device which may be adjusted to a desired angle of operation as may be required by the characteristics of the strip of sheet material passing through the looper.

55

In the following part of the specification the utility, advantages, and further objects of the invention will be more specifically pointed out.

Referring to the drawings which are for 60 illustrative purposes only,

Fig. 1 is an elevational view of simple and diagrammatic form showing the embodiment of my invention.

Fig. 2 is a fragmentary view taken sub- 65 substantially as indicated by the line 2—2 of Fig. 1.

Fig. 3 is a fragmentary view on the plane represented by the line 3—3 of Fig. 2.

Fig. 4 is a perspective view showing one 70 form of disalignment or twisting which occurs in the ordinary type of looper and results in breakage of the strip of sheet material from which the loops are formed.

In the simple form of apparatus illustrated 75 in the drawings a looper 11 is shown which includes a framework 12 having forward and rearward pairs of end posts 13 and 14 extending upwardly from a concrete foundation 15 which may consist of part of floor- 80 ing 16. The upper ends of the angles 17 which form the posts 13 and 14 are preferably tied together by a suitable brace or braces, such as indicated at 18. By means of sprockets 19 supported by brackets 20 which 85 extend from the frame 12, a continuous chain belt 21 is supported in substantially the manner shown in Fig. 1. The chain belt 21 includes laterally extending tubular rollers 22 which move forwardly in the direction indicated by the arrow 23 under a set of discharging rollers 24 over which a strip of sheet material 25 is continuously being discharged from an outlet 26 of what may be conveniently termed a primary machine.

95 By suitable mechanism operating in timed relationship to the movement of the strip of sheet material 25 from the outlet 26 of the primary machine, the chain belt 21 is caused to move forwardly in the direction of the ar- 100

row 23 in such a manner that consecutive loops 27 will be formed between and in such a manner as to hang from the tubular rollers 22, as indicated in Fig. 1. The forward end 28 of the sheet material 25 is carried, as indicated by the arrow 29, to a machine adapted for subsequent operation thereon, which machine I will hereinafter term the secondary machine.

10 During the periods of non-withdrawal of the forward end 28 of the strip of sheet material 25 from the looper 11, the strip being continuously fed into the looper from the rollers 24 will be formed in consecutive loops 27, the end or final loop 30 moving in leftward direction with the rollers 22 from which it is suspended, as also do each of the succeeding loops as each consecutive loop is formed.

20 As the material is drawn from the looper 11 in the direction of the arrow 29, the end loop 30 is shortened and then fully withdrawn, at which time the adjacent or sub-final loop 31 becomes the end loop and is itself shortened and removed by the action of withdrawing the forward end 28 of the strip of sheet material 25 from the looper 11. When the primary machine is stopped or when the withdrawing action is at any time 30 faster than the speed at which the sheet material is being fed into the looper 11, the position of the final loop will move in reverse direction, or rightwardly, as each final loop 30 is removed from the series of loops 27.

35 This temporary storage device or looper is of particular utility where the operation of the secondary machine is intermittent, as it enables the holding of the sheet in condition ready for utilization by the secondary machine.

40 The starting of an intermittent secondary machine produces an abrupt jerk on the primary loop 30, and where such primary loop 30 is allowed to hang in free suspension the result of the jerk at the start of the withdrawal of the strip of sheet material from the looper often produces an inverse twisting in the sheet material, as indicated at 32 in the end loop 30a shown in Fig. 4 in suspension from rollers 50 22a of a traveling chain belt. As the sheet material is drawn off in the direction of the arrow 33, Fig. 4, in using the standard type of looper, the disaligned or twisted portion 32 of the end loop 30a is drawn up between the rollers 22a and is caught thereat in such a manner as to result in breakage of the strip. This twisting or disaligning action is especially noticed where the strip of sheet material is impregnated with a substance which tends to stiffen or harden during the hanging of the strip in the form of loops in the looper, such a condition being found in the art of manufacturing roofing paper where 60 the strip consists of a sheet of felt or felt

paper impregnated with asphalt or similar substances.

70 My invention provides means for preventing such twisting, distorting, or disaligning of the strip of sheet material as set forth in the preceding paragraph, which means may conveniently consist of a plate or frame member 35 adapted to be applied against such of the consecutive loops as may be necessary to prevent twisting of the sheet material as it is 75 being withdrawn from the looper.

80 As shown in Figs. 2 and 3, the member 35 may include a wall structure 34 of sheet material or fabric supported as illustrated on a tubular frame 36 having rollers 37 at the upper and lower extremities thereof and being supported in adjustable relationship on a shaft or shafts 38 which extend between carriages 39 having rollers or wheels 40 which roll upon a pair of inclined tracks 41 which extend longitudinally of the looper between the uprights or posts 13 and 14. The tracks 41 slope rearwardly or downwardly in rightward direction so that the carriages 39 will tend, by gravity, to move in rightward direction, whereby to bring the restraining member 35 into engagement with the final or with the final and sub-final loops of such series of loops 27 as may exist in the looper 11.

85 As the number of loops 27 increases and as 90 the final and sub-final loops move leftwardly, the restraining member 35 is moved thereby in leftward direction against the action of gravity, tending to yieldably hold the restraining member 35 in rightward direction. 100

95 From Fig. 1 it will be perceived that the rollers 37 are parallel with the rollers 22 and that the restraining action of the member 35 results in the yieldable presentation of the rollers 37 and the sheet material 34 against 105 the sides of the final and sub-final loops 30 and 31, with the result that these loops are restrained from such freedom of movement as will permit them to become disaligned or twisted in such a manner that the strip of sheet material will be caused to break.

110 The restraining member 35 is adjustable from vertical position to a desired inclined position as a result of the provision of index plates 43 having holes 44 therein, as indicated in Fig. 1, through which retaining means in the form of bolts 45 may be passed for engagement with the side bars 46 of the member 35, as shown in Fig. 2.

115 The leftward posts 13 of the frame 12 are 120 provided with vertically aligned holes 48 whereby the leftward ends of the track members 41 may be raised or lowered, as desired, to change the slope thereof and to accordingly change the pressure with which the restraining member 35 is yieldably held against the final and sub-final loops 30 and 31.

125 In the use of this device I have found that the breakage of the strip of sheet material as 130 a result of twisting or disalignment thereof is

substantially entirely prevented, with the result that a worthwhile saving of time and labor is accomplished.

I have herein shown my invention in simple and practical form, but it is recognized that certain parts or elements thereof are representative of other parts, elements, or structures which may be employed in substantially the same manner to accomplish substantially the same results; therefore, it is not intended that the invention shall be limited to the details disclosed herein but shall have the scope set forth in the following claims.

I claim as my invention:

15 1. A device of the character described, including: a structure having means for supporting a loop of sheet material; and means engaging said loop in a manner to preserve practical alignment thereof, said means being rendered effective by the weight of said loop.

20 2. A device of the character described, including: a structure having means for supporting a loop of sheet material; and means frictionally engaging said loop in a manner to preserve practical alignment thereof.

25 3. A device of the character described, including: a structure having means for supporting a loop of sheet material; and aligning means for preserving alignment of said loop by engagement with an external face of said loop.

30 4. A device of the character described, including: a structure having means for supporting a series of loops of sheet material; and means frictionally engaging an external face of an end loop of said series of loops in a manner to preserve alignment of such end loop as it is being withdrawn from said device.

40 5. A device of the character described, including: a structure having means for supporting a series of loops of sheet material; and a restraining member yieldably present ed to the external face of the final loop of said series of loops.

45 6. A device of the character described, including: a structure having means for supporting a series of loops of sheet material; a restraining member for engagement with the final loop of said series of loops in a manner to preserve alignment thereof; and means for accomplishing the movement of said restraining member into yielding engagement with said final loop.

55 7. A device of the character described, including: a structure having means for supporting a series of loops of sheet material; a restraining member for engagement with the final loop of said series of loops in a manner to preserve alignment thereof; and a sloping track member for producing movement of said restraining member into engagement with said final loop.

60 8. A device of the character described, in-

cluding: a structure having means for supporting a loop of sheet material; a track sloping with respect to said structure; carriage means movable on said track; and a restraining member mounted on said carriage means in position to engage said loop. 70

9. A device of the character described, including: a structure having means for supporting a loop of sheet material; a track sloping with respect to said structure; carriage means movable on said track; and a restraining member adjustably mounted on said carriage means in position to engage said loop. 75

10. A device of the character described, including: a structure having means for supporting a loop of sheet material; and means engaging said loop in a manner to preserve practical alignment thereof, said means being adjustable for sheets of different mate- 80 rials. 85

11. A device of the character described, including: a structure having means for supporting a loop; means frictionally engaging said loop in a manner to preserve practical 90 alignment thereof; and adjusting means for varying the frictional engagement between said aligning means and said loop.

12. A device of the character described, including: a structure having means for supporting a loop of sheet material; and means engaging said loop for moving it from vertical in a manner to preserve practical alignment of said loop. 95

13. A device of the character described, including: a structure having means for supporting a loop of sheet material; and means engaging said loop for moving it from vertical an adjustable degree in a manner to pre- 100 serve practical alignment of said loop. 105

14. A device of the character described, including: a structure having means for supporting a loop of sheet material; and means engaging said loop in a manner to preserve practical alignment thereof and with a frictional force which is a function of the weight 110 of said loop.

15. A device of the character described, including: a structure having means for supporting a series of loops of sheet material; 115 and means engaging an end loop and pressing it against the adjacent loop of said series of loops in a manner to preserve alignment of such end loop as it is being withdrawn from said device. 120

16. A device of the character described, including: a structure having means for supporting a series of loops of sheet material; a restraining member for engagement with the final loop of said series of loops in a manner to preserve alignment thereof; means for controlling the pressure exerted on said final loop by said restraining member; and means for accomplishing the move- 125 130

ment of said restraining member into yielding engagement with said final loop.

17. A device of the character described, including: a structure having means for supporting a series of loops; a restraining member for engagement with the external face of the final loop of said series of loops in a manner to preserve alignment thereof; and gravity actuated means for effecting the engagement of said restraining means and said final loop.

18. A device of the character described, including: a structure having means for supporting a loop of sheet material; a track sloping with respect to said structure; means for varying the slope of said track; carriage means movable on said track; and a restraining member adjustably mounted on said carriage means in position to engage said loop.

20. In witness whereof, I have hereunto set my hand at Los Angeles, California, this 20th day of August, 1929.

RAY W. CONANT.
